CIGARETTE CASE

Warren R. Larter, South Orange, N. J., assignor
to Larter & Sons, Newark, N. J., a corporation
of New Jersey

Application September 26, 1933, Serial No. 690,977

2 Claims. (Cl. 206—41)

This invention relates in general to receptacles or cases and more particularly to a case for cigarettes to be carried in the pocket or handbag of the owner.

One object of the invention is to provide a case of this character which shall embody a novel and improved construction and combination of two complementary body sections and a latch section, hingedly connected together whereby the necessity for the usual spring catch or snap latch shall be eliminated, the case shall be simple in construction, attractive in appearance and easy and convenient to open and close.

Another object is to provide such a case wherein said body sections shall be concave and each shall be hingedly connected along the edge at one side to the corresponding side of the other by a spring hinge the normal tendency of which is to swing said sections apart, and wherein said latch section shall be hingedly connected by a spring hinge to one section at the side thereof opposite the hinge connection between said body sections and shall overlie the other body section to hold said sections together to close the case, whereby said case can be opened by simply swinging said latch section away from the body section so as to permit said body sections to spring apart.

Other objects are to provide a case of the character described which shall include a novel and improved cigarette holder for clamping the cigarettes between itself and one body section, said holder to be pivotally connected to the case under the influence of the spring of said hinge connection between the body sections, whereby the structure shall be simple and inexpensive; and to obtain other advantages and results as will be brought out by the following description.

Referring to the accompanying drawing in which corresponding and like parts are designated throughout the several views,

Figure 1 is a plan view of a cigarette case embodying my invention with portions broken away and shown in section.

Figure 2 is a transverse vertical sectional view through the case taken on the line 2—2 of Figure 1.

Figure 3 is a similar view showing the case open.

Figure 4 is a vertical longitudinal sectional view on the line 4—4 of Figure 2.

Figure 5 is an enlarged horizontal sectional view on the line 5—5 of Figure 4.

Figure 6 is an enlarged fragmentary transverse sectional view through the hinge connection between two body sections showing the case closed.

Figure 7 is a similar view showing the case open, and

Figure 8 is a detached perspective view of the spring strip for the hinge.

Specifically describing the illustrated embodiment of the invention, the case includes two body sections 1 and 2 which are preferably rectangular in plan view. Each section has a concave side, and the sections are arranged in superposed relation with their edges abutting so as to complement each other in forming the body of the case.

Each body section is hingedly connected at one edge along one side to the corresponding side of the other body section, and as shown, the body sections have a plurality of integral hinge tubes 3 and 4 respectively which are arranged in axial alignment with each other and in alternate relation longitudinally of the edges of the sections. Within the hinge tubes is arranged a flat spring strip 5 which has one end soldered or otherwise fixedly connected to one section as at 6 and its other end fixedly connected to the other section at 7. This spring strip serves as the pintle for the hinge connection and is placed under torque so that it normally tends to swing the body sections apart into the position shown in Figure 3 so as to open the case.

The body sections are held together so as to close the case by a latch section 8 which is hingedly connected to the edge of one of the body sections along the side thereof opposite the hinge connection between the body sections. As shown, the hinge connection of the latch section 8 with the body section, in the present instance the section 1, comprises a plurality of hinge tubes 9 on the latch section which are disposed in alternate relation and coaxially with hinge tubes 10 on the body section, and a flat spring strip 11 disposed within the hinge tubes and rigidly connected at one end 12 to the body section and at its other end 13 to the latch section. The spring strip 11 is placed under torque so as to normally influence the latch section into overlying and contacting relation to the body section 2 so as to hold the body sections together as shown in Figures 1 and 2. The latch section is of such shape and dimensions as to lie flat upon the exterior surface of the section 2 with the free end of the latch section remote from the hinge connection of the latch section with the section 2 the latch lever and complex difficultly operable coengaging hooks and lugs commonly used in latches are eliminated.

With this construction, and assuming the case

to be closed as shown in Figure 2, in order to open the case it is simply necessary to swing the latch section upwardly away from the body section 2 as shown in Figure 3, whereupon the spring 5 hinge connection between the body sections will swing the body sections apart to open the case. To close the case the body sections need merely to be pressed together and the latch section allowed to swing into contact with the body section 2 under the influence of its hinge spring 11. The latch section eliminates the necessity for the usual troublesome and complicated spring catch or snap latch, and the possibility of the case accidentally opening by releasing of the catch or latch is greatly reduced. The tendency of the body sections to spring apart is effectually restrained by the close proximity of the free edge of the body section 2 to the hinge connection of the latch section with the body section 1, and only slight spring resistance from the hinge spring 11 is necessary to hold the case closed.

It is desirable that the case be provided with a holder for clamping cigarettes securely against movement in the case, and for this purpose, I may provide a holder 14 having one end 16 connected to the hinge spring 5 so that said spring normally influences the holder toward the body section 1 to hold cigarettes A between the holder and the body section. The holder has a pivotal action 30 against the torque resistance of the hinge spring and may be swung upwardly into the position shown by dot and dash lines in Figure 3 to permit removal of the cigarettes from the case. To connect the holder to the hinge spring, certain 35 of the hinge tubes are cut away inwardly of the case as indicated at 17.

The invention provides an attractive case which is simple and inexpensive in construction and easy and convenient to open and close. While I have shown the invention as embodied in certain details of construction it should be understood that this is primarily for the purpose of illustrating the principles of the invention and

that the details of structure may be modified and changed by those skilled in the art without departing from the spirit or scope of the invention.

Having thus described my invention, what I claim is:

1. A cigarette case comprising two rectangular complementary body sections each having at the edge of one side a plurality of hinge tubes in alignment with and in alternate relation to the hinge tubes of the other section, a flat spring strip extending through said hinge tubes and rigidly connected at each end to one of said sections so that said sections are normally swung apart, the portions of adjacent hinge tubes within said casing being cut away to form an opening, a cigarette holder between said sections having one end in said opening and bent around said spring strip so that said holder is normally yieldingly influenced by said spring strip toward one section to clamp cigarettes between the holder and said section, and latch means for normally holding said sections together to close the case.

2. A case comprising two rectangular complementary concave body sections to be arranged in superposed relation with their edges at all sides abutting, a spring hinge connection between the edge at one side of each body section and the corresponding side of the other section so that said sections are normally swung apart to open the case, a latch section, and a spring hinge connection between said latch section and the edge of one of said body sections opposite said hinge connection between said body sections, for normally yieldingly influencing said latch section into overlying relation to the other body section to hold the case closed, the latch section lying flat upon the exterior of said body section and its free end being remote from said spring hinge connection between said latch section and said body section.

WARREN R. LARTER.
